UNITED STATES PATENT OFFICE.

JAMES R. ARMSTRONG, OF PITTSBURG, PENNSYLVANIA.

GAS-METER.

No. 889,652.

Specification of Letters Patent.

Patented June 2, 1908.

Application filed June 15, 1907. Serial No. 379,124.

To all whom it may concern:

Be it known that I, JAMES R. ARMSTRONG, a resident of Pittsburg, in the county of Allegheny and State of Pennsylvania, have invented certain new and useful Improvements in Gas-Meters, of which the following is a specification.

One object of this invention is to provide a meter with valve mechanism of improved 10 construction.

A further purpose is to so arrange the operating parts that it is impossible for the valve actuating mechanism to stop on a dead center.

15 The invention also includes certain improvements in the construction and arrangement of the gas measuring chambers, particularly the formation thereof in connection with a central casing and opposite chambers forming shells secured thereto, whereby the parts are easily assembled and passages of 20 large area are provided for the gas.

In the accompanying drawings, Figure 1 is a vertical sectional view of the improved 25 meter. Fig. 2 is a vertical cross sectional view, taken on line 2—2 of Fig. 1. Figs. 3 and 4 are sectional plan views, taken on lines 3—3 and 4—4, respectively, of Fig. 1.

Referring to the drawings, the body of the 30 meter consists of a central frame or casing 2 which is divided by partitions into several compartments or chambers, as hereinafter described, and at opposite sides of the casing are the circular upright heads 3 having the 35 annular extension plates 3' to which are secured the sheet metal caps or shells 4, 4'. A portion of the length of casing 2 is divided by vertical longitudinal partition 5 into chambers 6 and 6' which are open at their outer 40 faces, as shown. Secured to the outer faces of heads 3 are the collapsible bellows 7 carrying, respectively, the diaphragm plates 8 and 8' which operate in the spaces inclosed by shells 4, 4', thus forming two pairs of 45 measuring chambers, the chambers of each pair being separated by the diaphragm which constitutes a movable wall for each. Thus, one pair consists of chamber 6 having diaphragm 8 as an outer wall and chamber 9 50 formed by the space between the outer face of said diaphragm and shell 4. Similarly, the other pair of chambers consists of the inner chamber 6' and the outer chamber 9', the latter formed by the space between dia- 55 phragm 8' and shell 4'.

At the top of casing 2 is a transverse inlet

chamber 10 having valve seats formed in the bottom thereof, with ports 11 and 11' opening into chambers 6 and 6', respectively.

The end of casing 2 opposite chambers 6 and 6' is partitioned centrally at 12 to form chambers or passages 13 and 13' which are open at their outer sides at 14 to communicate with the outer measuring chambers 9 and 9', respectively. Chambers 13 and 13' have ports 15 and 15', respectively, opening through the valve seat of inlet chamber 10. Casing 2 is also formed with the transverse outlet chamber 16, located between chambers 6, 6' and 13, 13', and open at its top 70 through the valve seats, as shown.

Each of the diaphragm plates is supported by a horizontally swinging hinge member 17, pivoted at 17' to casing 2, with the free end of the hinge pivoted at 17'' to arms 18 and 18' secured to the inner face of the diaphragm. The upper arm 18 is extended inward beyond the hinge and connected thereto is the swinging rod 19 which has a movement parallel with hinge 17 and prevents the 80 diaphragm plate from tilting or tipping, causing the same to remain constantly parallel with head 3.

Within each of chambers 6 and 6' is a vertical crank shaft 20 connected by rod 21 with hinge 17. The lower coned ends of shafts 20, as also the lower ends of hinge pivots 17', turn in the aluminum cup bearings 22 seated in the floors of chambers 6 and 6'. Shafts 20 extend through the tops of said chambers 90 and carry gear wheels 23, 23', respectively, which mesh with each other, thus causing the diaphragms to operate in unison.

The admission of gas to the measuring 95 chambers, and the passage of the measured gas from the latter to outlet 16, is controlled by two slide valves 24 and 24' which operate on the valve seats in the bottom of inlet chamber 10, each valve carrying a pin 25 projecting downwardly through a slot 25' in 100 the bottom of the inlet chamber, and these pins are connected within measuring chambers 6 and 6' by pitmen 26 with shafts 20. Each of the valves is formed with an intermediate upwardly-arched portion 27 and flat 105 end portions, as shown, so that in one position of the valve, port 11 of chamber 6 is in communication with outlet 16, and port 15 of chambers 13 and 9 is open to the inlet chamber 10, thus filling the outer chamber as 110 the inner chamber 6 empties. Also formed on each valve is a tongue 27' which covers

slot 25' when the valve is in outward position.

Each of the valves is of such size as to momentarily cover the ports of both of its measuring chambers at the same time, and this occurs upon each reciprocation of the valve when its pitman is halfway between its dead center positions. At the same instant the pitman of the other valve is moving over 10 one of its dead center positions with one of the measuring chamber ports fully open, thus admitting a full volume of gas to that chamber and affording maximum pressure upon the diaphragm which prevents the crank shaft from stopping with its valve pitman in a dead center position. In other words, one valve moves a quarter stroke 15 ahead of the other valve, with the result that neither valve can become stalled, thus rendering it impossible for the meter to cease to 20 operate.

The crank stem 28 may be engaged by the pin 29 carried by one of the gear wheels for operating the registering mechanism, not 25 shown. Casing 2 and heads 3 are preferably formed of cast metal, and as the diameter of 30 said heads is smaller than that of the outer measuring pockets inclosed by shells 4, 4', the heads are extended by the annular sheet 35 metal plates 3', and the inner edges of these plates and the inner edges of the bellows 7 are secured to heads 3 by clamping rings 30. The outer edges of plates 3' are turned laterally and jointed with shells 4, 4' like a black- 40 ing box, and this joint is preferably secured and sealed by the encircling sheet metal strap 31 which is soldered.

With a meter constructed as here shown, the valve actuating mechanism is inclosed 45 within the measuring chambers. Also, the gas has full and free access to all the measuring chambers, particularly the outer chambers, there being no pressure-consuming tortuous passages. And the construction which produces these results is extremely simple and the parts are easily assembled.

I claim:—

1. The combination of an inlet chamber, measuring chambers having ports opening 50 into the bottom of the inlet chamber, a diaphragm separating the measuring chambers, an outlet, a slide valve in the bottom of the inlet chamber for controlling the passage of gas therefrom to the measuring chambers 55 and from the latter to the outlet, and mechanism located within one of the measuring chambers for operatively connecting the diaphragm and valve.

2. The combination of measuring chambers, an inlet chamber having ports in its bottom communicating with the measuring chambers, an outlet, a valve for controlling the passage of gas from the inlet chamber to the measuring chambers and from the latter 65 to the outlet, a diaphragm separating the

measuring chambers, a crank-shaft within one of the measuring chambers and operatively connected to the diaphragm, and a rod within said measuring chamber and extended from the crank-shaft toward the port 70 opening into the inlet chamber and there connected to the valve.

3. In a meter, the combination of two measuring chambers, a diaphragm forming a movable wall between the chambers, a hinge member connected to and movable with the diaphragm, a crank shaft connected to and adapted to be rotated by the hinge member, gas inlets and outlets for the measuring chambers, and a slide valve operatively connected to the crank shaft for controlling the gas inlets and outlets. 75

4. In a meter, the combination of measuring chambers, a gas inlet and an outlet, a valve for controlling communication between each chamber and the inlet and outlet, a diaphragm, a crank shaft in one of the chambers and operatively connected to the diaphragm, and a rod within the shaft-contained chamber and connecting the shaft 80 and valve. 85

5. In a meter, the combination of measuring chambers, an inlet chamber having ports communicating with the measuring chambers and also a slot opening into one of the chambers, a slide valve in the inlet chamber for controlling the ports, the valve having an extension for covering said slot, a diaphragm, and means located wholly within one of the measuring chambers and 95 operative through the slot for connecting the valve and diaphragm. 100

6. In a meter, the combination of two pairs of measuring chambers, diaphragms forming movable walls between the chambers of each pair, two shafts each connected to and adapted to be rotated by the diaphragms, intermeshing gear wheels driven by the shafts, gas inlets and outlets 105 for the measuring chambers, and valves 110 operatively connected to the shafts for controlling said inlets and outlets.

7. In a meter, the combination of two pairs of measuring chambers, diaphragms forming movable walls between the chambers of each pair, a crank shaft connected to and adapted to be rotated by each diaphragm, intermeshing gears driven by the shafts, gas inlets and outlets for the measuring chambers, valves for controlling the 115 inlets and outlets, and pitmen connecting the cranks of said shafts with the respective slide valves. 120

8. In a meter, the combination of a central casing, the opposite chamber-inclosing 125 heads secured to opposite sides of the casing, one portion of the casing being partitioned centrally and open at its outer sides, diaphragms secured to the open outer sides of the casing, each diaphragm forming a 130

movable wall separating a pair of measuring chambers formed by the partitioned casing and said heads, the casing having an outlet chamber common to the measuring 5 chambers, an inlet chamber above the outlet chamber and open to all the measuring chambers, a pair of slide valves within the inlet chamber—one for each pair of measuring chambers—for controlling the passage of gas thereto and therefrom, and operative connections between the valves and the diaphragms.

9. In a meter, the combination of a central casing open at its outer sides and at one 15 end partitioned to form chambers 6, 6', and at its opposite end partitioned to form chambers 13 and 13', an inlet chamber above and having ports opening into all the chambers, an outlet adapted to coöperate 20 with all of said ports, heads inclosing the outer open sides of the central casing, dia-

phragms within said heads, with their bellows respectively separating chambers 6 and 13 and 6' and 13', and valve mechanism operatively connected to the diaphragms. 25

10. In a meter, the combination with a diaphragm, of a hinge member having a fixed mounting and a pivotal connection with the diaphragm so as to move therewith, and a guide rod paralleling the hinge member with one end of the rod pivoted to a fixed part and the other end having a pivotal connection with a diaphragm, whereby the latter is prevented from tilting or tipping. 35

In testimony whereof I affix my signature in presence of two witnesses.

JAMES R. ARMSTRONG.
